ATTORNEY

UNITED STATES PATENT OFFICE.

HENRY STUEBNER, OF PHILADELPHIA, PENNSYLVANIA.

ELECTRICAL SWITCH.

SPECIFICATION forming part of Letters Patent No. 543,409, dated July 23, 1895.

Application filed January 19, 1895. Serial No. 535,457. (No model.)

To all whom it may concern:

Be it known that I, HENRY STUEBNER, a citizen of the United States, residing in the city of Philadelphia, State of Pennsylvania, have 5 invented certain new and useful Improvements in Electrical Switches, of which the following is a specification.

My invention is more particularly a double push-button switch to be used in systems of 10 electric lighting and general distribution. It is designed for making and breaking the current in a double-pole system, or where main and distribution circuits are employed to close and open a double set of contacts. It 15 may, however, be used in a single-pole switch for closing and opening a single set of contacts and generally for making and breaking any circuit.

The specific object of the invention is to produce 20 a quick-acting switch of simple, compact, and economical construction and to overcome arcing and burning, which results sometimes from the construction or improper use of switches.

25 The invention is illustrated in the accompanying drawings, in which—

Figure 1 is a side view of the mechanism with the circuits closed, the casing being broken away for the purpose of illustration.

30 Fig. 2 is a view of the face-plate. Fig. 3 is a view of the side opposite that shown in Fig. 1 with the circuits opened, the casing being broken away for the purpose of illustration.

Fig. 4 is a sectional view in the direction of 35 the arrow on the line A A of Fig. 1. Fig. 5 is a sectional view in the direction of the arrow on the line A' A' of Fig. 3. Fig. 6 is a side view of the push-rod and cross-bar carrying the bridges. Fig. 7 is a back view of the bearing-block. Fig. 8 is a side view of the short push-rod.

The casing 1, of hard rubber or other insulating material, is preferably made in a solid piece with a recess to receive the mechanism, which when inserted is inclosed by the face 2, having screw-holes 63 for securing the plate to the bearing-block 5, 61 for securing it to the casing, and 60 for securing it over the opening which receives the casing.

50 Openings 62 and 64 permit the operation of the push-buttons on the ends of the push-rods 3 and 4, the latter moving in bearings 70 and

71 in the block 5. The movements of these rods are limited by the pins 6 and 7 integral therewith, which play in the slots 8 and 9, and 55 their relative actions are secured by means of the spring 27, which is coiled around the hub 10, while its ends engage the pins 6 and 7.

A catch 21 is pivoted to the rear of the bearing-block on the screw 22, the end 23 of 60 this catch being held in constant contact with the surface 16, 15, or 14, or in engagement with the notch 13 of the rod 4, while its opposite end engages the notch 17 or bears against one of the surfaces 18, 19, or 20 of the rod 3. This 65 action of the catch is effected by means of the coiled spring 29, seated in the recess 26 of the bearing-block and bearing outward against the projection 25 of the arm 24.

A cross-bar 11 of insulating material is 70 secured on the end of the push-rod 3, and conducting pins or bridges 12 and 12' extend through the ends of the cross-bar, and when the mechanism is in the position shown in Fig. 1 close the circuits. In this position current from the main or supply wire 40 will pass 75 through the corresponding binding-plug 30, the contact-clip 53, the bridge 12, the clip 52, the second binding-plug, and the wire 41 through the distribution system, returning by 80 the wire 42 and its binding-plug to the clip 51, thence through the bridge 12', the clip 50, the corresponding binding-plug, and the return-wire 43 of the main system to the source of 85 electric energy.

The binding-plugs 30 are seated in the rear wall of the casing, and are provided with sockets 31 to receive the ends of the wires which are held in place by the binding-screws 32, the plugs also holding the clips in place 90 by a screw or other suitable engagement.

In the position of the mechanism shown in Fig. 3, the end 23 of the catch lies in the notch 13 of the rod 4, thus holding the rod, while the opposite end of the catch bears against 95 the surface 20 at the foot of the incline 19 of the rod 3, this rod being held in position by the spring 27, one end of which engages the pin 7 while the other end is held by the pin 6. When pressure is applied to the button 100 on the rod 3 the rod moves in, tightening the coil of the spring 27 about the hub 10, while the incline or wedge surface 19 rocks the catch 21 until the junction of the incline and

the surface 18 is reached. At this point the end 23 of the catch clears the notch 13, and the accumulated tension of the spring 27 instantly throws the short rod 4 outward, and 5 the resistance of the spring having been withdrawn from the pin 7 the rod 3 flies in and is held by the engagement of the catch with the notch 17, the parts taking the position shown in Fig. 1.

10 When the current is to be cut out, the button of the rod 4 is pressed in, but the rod 3 and the bridges 12 and 12' will not move until the incline 15 has rocked the catch 21 until it clears the notch 17, when the rod 3 is 15 thrown outward by the tension of the spring 27 breaking contact instantly.

If, as sometimes happens, the rod 4 is held in while pressure is applied to the rod 3, the latter will move in until its movement has 20 coiled the spring 27 till it binds upon the hub 10. The inward movement is checked at this point before partial contact is made, the spring being readily regulated to check the inward movement at the point desired. It 25 will be seen that the contact at the beginning of making and the end of breaking will be a single point, the tangent point of the bridges and clips. This construction reduces flashing.

It will be evident to those skilled in the art 30 that minor changes may be made in the mechanism without departing from the spirit of my invention, and I do not wish to be understood as limiting myself to the specific details shown and described.

35 Having described my invention, I claim as new and desire to secure by Letters Patent—

1. In a mechanical movement, two reciprocating push rods, a block provided with seats for the said push rods and having a hub, in 40 combination with a spring coiled about the said hub and having its ends in direct engagement with the push rods, substantially as shown and described.

2. In a mechanical movement, in combination, two reciprocating push rods, means for holding each of the rods until the other has moved a predetermined distance, a spring coiled about a fixed hub and having its ends in engagement with the push rods, and means 45 for releasing each of the rods when the other has moved a predetermined distance, substantially as shown and described.

3. In an electric switch, in combination, two

reciprocating push rods, a catch which directly engages and holds each until the other 55 has moved a predetermined distance, means for withdrawing the catch from each when the other has moved a predetermined distance, a conducting bridge and a pair of contact clips, substantially as shown and described.

4. In an electric switch, a reciprocating push rod and cross-bar rigidly secured thereto carrying one or more conducting bridges, in combination with one or more sets of contact clips, 65 a catch for holding the bridge or bridges in contact with the clips, a spring for effecting the break of contact, and a second reciprocating rod for actuating the said catch and spring, substantially as shown and described. 70

5. In an electric switch, two reciprocating push rods each having a projecting pin extending therethrough; a block having a hub, bearings for the said rods, and slots to limit the movements of the said pins and rods; in combination with a spring coiled about the 75 said hub and having its ends in engagement with the said pins, substantially as shown and described.

6. In an electric switch, two reciprocating 80 push rods each having a projecting pin extending therethrough; a block having a hub, bearings for the said rods, and slots to limit the movements of the said pins and rods; in combination with a spring coiled about the 85 said hub and having its ends in engagement with the said pins; and a catch for holding each rod until the other has moved a predetermined distance, substantially as shown and described. 90

7. In an electric switch, two reciprocating push rods each having a transverse projection, a notch, and an incline; a block having a hub, bearings for the said rods, and slots to limit the movements of said rods; in combination with a spring coiled about the said hub and having its ends in engagement with the said rods; and a spring actuated catch for engaging the notch of each rod until withdrawn by the incline on the other, substantially as shown and described. 95 100

HENRY STUEBNER.
